UNITED STATES PATENT OFFICE.

JULIAN KENNEDY, OF PITTSBURGH, PENNSYLVANIA.

ELEVATOR TOWER FOR BLAST-FURNACE STRUCTURES.

Application filed April 4, 1925. Serial No. 20,753.

The present invention relates to elevator towers, and more particularly to elevator towers for blast furnace structures.

The elevator tower is made of tubular form and does not require external bracing except for the attachment of the tower, at its top, to the blast furnace structure. The tubular tower also provides protection for the workmen against the inclemencies of the weather, or against gases in case of explosions. The structure is also relatively cheap to build.

In the drawings, which illustrate the preferred embodiment of the invention,

15 Figure 1 is a side elevation of a portion of a blast furnace structure showing the elevator tower in combination therewith;

20 Figure 2 is a front elevation, partly broken away and on an enlarged scale, of the installation shown in Figure 1;

25 Figure 3 is a transverse sectional view on an enlarged scale along the line III—III of Figure 1;

Figure 4 is a transverse sectional view on an enlarged scale, and partly broken away, along the line IV—IV of Figure 1;

30 Figure 5 is a transverse sectional view on an enlarged scale, along the line V—V of Figure 1;

35 Figure 6 is a transverse sectional view along the line VI—VI of Figure 1, and

Figure 7 is a longitudinal sectional view on an enlarged scale, on the line VII—VII of Figure 6.

40 The elevator tower 2 is of tubular form, preferably of a circular cross section. The tower is built up of a number of rings or bands 3 and 3' joined together by rivets 4. The riveted joints are preferably water and gas tight and may be calked if necessary.

45 The tubular construction, and particularly the construction shown, which consists of the superposed circular rings, is inherently rigid and strong and there is no necessity for supplemental bracing or sheathing to stiffen the tower structure.

50 The tower is supported against wind pressure by a suitable bracing connection with the blast furnace structure. In the illustrated construction the top of the tower is connected with the upper end of one of the hot stoves 5 by a bracing connection 6. The bracing connection 6 is in the form of a platform made of plates and connected to the hot stoves and to the elevator tower. This connection, being formed of horizontal

55 ly disposed plates, rigidly resists the transverse stresses exerted by the wind pressure on the elevator tower, but will yield vertically to allow for the necessary differences in 60 expansion of the furnace structure and the elevator tower under different temperature conditions. It is found that the plate construction shown is sufficiently flexible to take care of the differences in expansion 65 without the necessity of connections allowing lost motion.

70 While I have shown the bracing connection for the elevator tower as connected to one of the hot blast stoves 5, it is to be understood that the elevator tower may have its bracing connection with another part of the blast furnace structure, as, for example, to the furnace proper or to the stack.

75 Since the tower is firmly braced against wind pressure by its connection with the blast furnace structure, the lower end of the tower need not be braced against deflection, but may be simply set on any suitable support. In the drawings there is shown a projecting foot 7 which serves as a supporting bearing for the bottom of the tower and may rest on any suitable foundation, such as a stone or cement foundation.

80 The tubular body of the tower is closed except for the door 8 at the bottom of the tower and a door 9 at the top of the tower. The door 9 opens on a platform or run-way 10 which extends over the tops of the hot stoves 5. This platform also extends to 85 the top of the blast furnace proper and to such other places in the structure to which access is desired. The platform 10 is formed with an extension 13 leading to a ladder tower 14 projecting from one side of the 90 elevator tower 2 by means of which access is provided to the landing 15 leading to the motor room 16 at the top of the elevator tower. The motor room 16 has openings 17 and 19 through its floor for the cables 18 leading to the top of the elevator cage 18 and to the counter-weight 20. It may be 95 braced as desired to support the motors and other equipment and is preferably formed with a trap-door 21.

100 While the elevator cage 18 may be of any desired construction, I prefer to use a cage of substantially rectangular cross section having guides 22 at its diagonally opposite corners adapted to cooperate with rails 23 105 supported on the inside of the elevator tower. The rails are preferably supported

by the braces, each comprising sections 24 and 25 riveted together and secured to the rails 23 and to the tubular tower structure. The counter-weight 20 slides in the space 5 between one of the sides of the cage and the inside of the tower and is guided by rails 26 carried by braces 27 secured to the inside of the tower.

The tubular tower not only serves as an 10 efficient protection to the workmen against the weather and against gases in case of explosions, but is inherently strong and economical to build. While a tubular tower of various cross sections may be built, I prefer to build the tower as shown of a number 15 of superimposed circular plates or rings. These may be made of sufficient gauge to furnish the necessary rigidity to the tower structure without the necessity of interior 20 bracing so that the entire space within the tower is available for the cage and counter-weights. The circular plate construction is also relatively cheap to fabricate and assemble. Since the tubular tower is, in itself, 25 inherently strong and rigid there is no necessity for any intermediate bracing or connections to the ground. The bracing connection near the top of the tower to the blast furnace structure is sufficient in itself to resist 30 any wind pressure to which the elevator tower may be subjected. This does away with the necessity of guy-wires or other bracing structural work which might interfere with the operation or repair of the furnace. 35 The bracing connection shown is simple but effective in resisting the lateral thrusts due to wind pressure, while at the same time permitting the necessary relative vertical movement between the furnace structure and the elevator tower.

The present invention is not limited to its illustrated embodiment, but may be otherwise embodied within the scope of the following claims.

45 I claim:

1. The combination with a blast furnace structure, of an auxiliary vertical tubular elevator tower having a bracing connection with the furnace and closed throughout its 50 length and having openings at its bottom and top, and having a gas-excluding door

for at least one of said openings, substantially as described.

2. The combination with a blast furnace structure, of an auxiliary vertical tubular 55 elevator tower having a bracing connection with the furnace and closed throughout its length and having a gas-excluding door at its bottom, substantially as described.

3. The combination with a blast furnace 60 structure, of an auxiliary vertical tubular elevator tower having a bracing connection with the furnace structure and closed throughout its length and having gas-excluding doors at its top and bottom, sub- 65 stantially as described.

4. The combination with a blast furnace structure, of an auxiliary cylindrical vertical tubular elevator tower, and a vertically yielding bracing connection between 70 the top of the tower with one of the stoves, said tower being closed throughout its length and having gas-excluding doors at its top and bottom, substantially as described.

5. The combination with a blast furnace 75 structure, of an auxiliary cylindrical vertical tubular elevator tower loosely supported upon the ground and having a vertically yielding bracing platform of plate construction connecting the top of the tower 80 with one of the stoves, said tower being closed throughout its length and having gas-excluding doors at its top and bottom, substantially as described.

6. The combination with a blast furnace 85 structure, of an auxiliary vertical elevator tower of closed tubular plate construction having its lower end unbraced and having a vertically yielding bracing connection between the upper part of the tower and the 90 furnace structure, substantially as described.

7. The combination with a blast furnace structure, of an auxiliary vertical elevator tower of closed tubular plate construction having its lower end unbraced from the 95 ground and having a vertically yielding bracing platform of plate construction connecting the upper part of the tower with one of the stoves.

In testimony whereof I have hereunto set 100 my hand.

JULIAN KENNEDY.
